(57) **CLAIM**

The ornamental design for a photograph display and growth chart, as shown and described.

DESCRIPTION

FIG. 1 is a front elevational view of the photograph display and growth chart showing my design;

FIG. 2 is a rear elevational view thereof;

FIG. 3 is a right side elevational view thereof, the side opposite being a mirror image;

FIG. 4 is a top plan view thereof;

FIG. 5 is a bottom plan view thereof; and,

FIG. 6 is a perspective view thereof.

The broken lines showing the photographs are for illustrative purposes only and form no part of the claimed design.

1 Claim, 2 Drawing Sheets

FIG. 1**FIG. 2****FIG. 3**

FIG. 4**FIG. 5****FIG. 6**
